WINDOW LOCKING DEVICE

Henry Sarrasin, Providence, R. I.

Application July 29, 1931. Serial No. 553,765

5 Claims. (Cl. 292—202)

This invention relates to a window locking device and has for its object to provide a lock to secure the sliding sashes of the window in partly opened position.

5 Another object of this invention is the provision of a construction which cannot be manipulated with a stick or the like, for releasing the same by reaching through the open part of the window.

10 Another object of this invention is the provision of a construction which may be manually released from locking position and moved to a position to permit passage of the sashes of a window, one by the other.

15 Another object of this invention is the provision of a simple mounting and locking means which may be released to permit movement of the locking portion of the device from obstructing to non-obstructing position without detachment and removal of any of the parts.

20 A further object of this invention is the provision of a pair of hinged members with an abutment member threadedly engaging both members for locking in one position but permitting partial withdrawal from this locking position for the parts to be swung on the hinge to inoperative position.

With these and other objects in view, the invention consists of certain novel features of construction, as will be more fully described, and particularly pointed out in the appended claims.

30 In the accompanying drawing:

Fig. 1 is a perspective of the device mounted upon one of the upright portions of the window sash and in operative position.

35 Fig. 2 is a perspective view, similar to Fig. 1, showing the device in inoperative position.

Fig. 3 is a side elevation of the device showing fragmental portions of two window sashes, 40 the device being in operative portion, and showing one of the sashes as abutting a portion of the device in the path of its movement to prevent opening movement of this sash.

Fig. 4 is a view, similar to Fig. 3, showing the 45 device in inoperative position with the sash moving in its path past the device.

Fig. 5 is a central sectional view through the device.

Fig. 6 is a fragmental sectional view on an 50 enlarged scale, showing the threads in both the base and mounting members and the threaded shank of the abutment member in engagement therewith.

It is frequently desirable to leave the windows 55 of a house in partly opened position for venti-

lation or the like, and to provide a means for locking the windows in this partly opened position, and in order to accomplish this result, I have provided a device which may be mounted upon one of the window sashes and which will have a portion extending into the path of movement of the other window sash to abut therewith, and prevent further opening of the window and in order that this device may be moved from such locking position without the complete removal of the device from the sash, I have hinged the abutment part to a base portion thereof so that it may be swung from abutting or operative position to inoperative position, and the following is a detailed description of the present embodiment 70 of this invention, illustrating the preferred means by which these advantageous results may be accomplished.

With reference to the drawing, 10 designates a base plate or member provided with bevelled edges 11 and 12 to provide a better appearance and a base less liable to abrade parts coming in contact therewith. The base is provided with hinge lugs 13 and 14, between which there is positioned the bearing portion 15 of the mounting member 16 and through which hinge lugs and bearing portion a pin 17 extends to hingedly mount these two members together. A recess 18 is provided in the face of the base member of a depth substantially the thickness of the mounting member 16 to receive this mounting member therein, so that its outer surface may be flush with the base.

A threaded opening 19 is provided in the mounting member and a threaded opening 20 in the base member in the recess portion thereof, which openings register when the mounting member is a said recess and which openings threadedly receive the stud portion 21 of the abutment member 22 which is provided with a handle portion 23 having recesses 24 therein to provide a better gripping surface for manual rotation.

In use, the base member 10 is mounted upon the upper sash 25 of a window by suitable screws extending through openings therein, which sash carries a pane of the glass 26, the location being about six inches above the joint of the sashes when in closed position. When I desire to lock the window so that the sashes may be opened about six inches, the abutment member 22 is located in the position illustrated in Fig. 1, with the shank portion 21 thereof engaging both of said threaded openings 19 and 20, to lock the mounting member and the abutment member in the desired position to obstruct the passage of

110

the sash 27, by reason of the upper horizontal bar 28 thereof, engaging the abutment member 22 as illustrated in Fig. 3. This position of the device permits the limited opening of the window, and as it is necessary to rotate the round abutment to unlock the same, this cannot be accomplished by the use of a stick manually manipulated through the opening in the window.

It is, of course, understood that should a different or larger amount of opening be desired, the base will be accordingly shifted further from or nearer to the junction of the sashes.

Should it be desired to permit free passage of the sashes 25 and 27, one by the other, I rotate the abutment member 24 by engagement with the handle 23, to withdraw its shank portion 21 from the base member 10, leaving the same threadedly engaging the mounting member 16, thus permitting the mounting member to be swung about its hinge to the position illustrated in Figs. 3 and 4, whereby the sash 27 may be moved freely past the sash 25 or vice versa, leaving the windows entirely unobstructed and free to move as if the device were removed from its position.

In describing the position of the device, as being placed on the upper sash, I have assumed that the lower sash will slide along the face of the upper sash on which face the abutment member is mounted. It will also be understood that in some cases, instead of swinging the mounting member and the abutment member therewith, I may completely remove the abutment member 22 by a further withdrawing rotation of the abutment member to completely remove it from the mounting member.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A locking device for a window having sliding sashes comprising a base member provided with a threaded opening therein a mounting member hinged to said base and having an opening therein, an abutment member having a threaded portion rotatably engaging said mounting member and threadingly engaging said base member whereby it may be detached from said base member by rotation thereof to swing with said mounting member out of working position.

2. A locking device for a window having sliding sashes comprising a base member provided with a threaded opening therein, a mounting

member hinged to said base and having a threaded opening, an abutment member having a threaded portion threadingly engaging said mounting member and threadingly engaging said base member whereby it may be detached from said base member by rotation thereof to swing with said mounting member out of working position.

3. A locking device for a window having sliding sashes comprising a base member having a threaded opening therein, a mounting member hinged to said base and having an opening therein, an abutment member having a threaded portion rotatably engaging said mounting member and threadingly engaging said base member whereby it may be detached from said base member by rotation thereof to swing with said mounting member out of working position, said abutment member being provided with a handle portion having recesses therein for rotation of the same.

4. A locking device for a window having sliding sashes comprising a base member to be secured to one sash of a window, a mounting member hinged to said base member, said members having threaded openings aligning when the mounting member is in engagement with said body, an abutment member having a threaded shank to enter said threaded openings for securing the mounting and base members together and itself in the path of movement of the other sash of the window, said abutment member being rotatable to withdraw it from the threaded opening in said base member and cause it to be carried wholly by the mounting member whereby it may be swung on its hinge to remove the abutment member from the path of movement of the said other sash.

5. A locking device for a window having sashes comprising a base member having a face recess therein to be secured to one sash of a window, a mounting member fitting said recess and hinged to said base member, said members having threaded openings aligning when the mounting member is in said recess, an abutment member having a threaded shank to enter said threaded openings for securing the mounting and base members together and itself in the path of movement of the other sash of the window said abutment member being rotatable to withdraw it from the threaded opening in said base member and cause it to be carried wholly by the mounting member whereby it may be swung on its hinge to remove the abutment member from the path of movement of the said other sash.
